ESCUTCHEON PLATE

La Verne E. Clayton, Rockford, Ill., assignor to Amerock Corporation, Rockford, Ill., a corporation of Illinois

Application March 20, 1957, Serial No. 45,359

Term of patent 14 years

(Cl. D50—6)

Fig. 1 is a front view of an escutcheon plate showing my new design.

Fig. 2 is a perspective view of the escutcheon plate.

Fig. 3 is an enlarged sectional view taken along the line 3—3 in Fig. 1.

Fig. 4 is an enlarged sectional view taken along the line 4—4 in Fig. 1.

Fig. 5 is an enlarged fragmentary sectional view taken along the line 5—5 in Fig. 1.

I claim:

The ornamental design for an escutcheon plate, substantially as shown.
